UNITED STATES PATENT OFFICE.

HENRY L. NODLER, OF COVINGTON, KENTUCKY.

SWITCH-MOVEMENT FOR STREET-RAILWAYS.

SPECIFICATION forming part of Letters Patent No. 426,306, dated April 22, 1890.

Application filed July 30, 1889. Serial No. 319,220. (No model.)

To all whom it may concern:

Be it known that I, HENRY L. NODLER, a citizen of the United States, residing at Covington, in the county of Kenton and State of Kentucky, have invented certain new and useful Improvements in Switch-Movements for Street-Railways; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to an improved mode of operating street-railway switches; and it consists of a stationary device operated from the street-car, by which, in conjunction with other devices connected to the switch, the same is manipulated.

The object of this invention is to provide means whereby the switch may be worked easily, quickly, and surely without slowing up the car and without the danger of missing or overrunning, as all working parts work within fixed and previously-arranged limits. I attain these objects in the accompanying drawings, in which—

Figure 1 is a top view of a switch and adjacent portions of track, showing, also, in dotted lines part of street-car above. Fig. 2 is a side view or vertical elevation of the part illustrated before, showing parts of the street-car in full lines. Fig. 3 is a longitudinal vertical section on line 3 3 of Fig. 1. Fig. 4 is a vertical cross-section on line 4 4 of Fig. 1. Fig. 5 is a perspective view of the shifting-frame 10.

7 is the switch-plate, and 8 the switch.

9 are portions of the track.

10 is a shifting-frame pivoted at 11, and loosely connected with switch 8 by means of a pin 12.

13 is another plate below frame 10, having two vertical flanges 14 14, and is rigidly secured to the switch-plate or to ties below. Part 15 of frame 10 moves in a groove cut out of the bottom of the track in the switch-plate, so as to bring it below the action of the wheels, as shown at 16, Figs. 1 and 3. Part 17 of frame 10 may be entirely below the track, as shown at 18, Figs. 1 and 3. Frame 10 might

be pivoted to the switch-plate; but more preferably it is pivoted to plate 13.

19 is a roller journaled onto a vertical shank 20, and is ordinarily kept up by a spring 21. 55 The upper end of this shank 20 may be provided with a treadle 22 if to be operated accordingly, or if to be manipulated by hand a suitable lever-connection 23, as indicated by dotted lines, may be provided. Where cars 60 always make turns in only one direction, one roller is sufficient. Otherwise one or two must be put on each side, as the particular case may require it.

The operation is as follows: The car approaching the switch, roller 19 is pressed, either by foot or hand, whatever way is used, down, so it may enter between one of the flanges 14 and the adjacent part 24 of frame 10, at which moment the parts are in a position as shown at 25, Fig. 1. At 26 in Fig. 1 and in Fig. 4 the roller has entered between parts 14 and 24 and the switch is about set. Having passed over the switch, the operator releases his hold on the upper connection of 75 roller 19 and the same is returned to its normal position by spring 21. In place of the roller 19, a solid wedge-shaped cam might be used; but I prefer the former, as it causes less friction. Upright flanges 14 and plate 80 13 are not absolutely needed as far as operating the device is concerned. Their main object is to protect the exposed parts of frame 10 and to guide roller 19 properly against part 24 of frame 10. 85

In the present case the parts attached to the car are inside of the platform. They could, however, be located outside, if preferred.

Having described my invention, I claim as new— 90

1. In combination with a switch, the frame 10, pivoted at its forward end and carrying on its other end the switch pivotally connected, and having upright flanges 24 connected with each other by the front and rear 95 parts 15 and 17 of said frame passing underneath the track and capable of being acted upon and displaced by a suitable apparatus from the car, all as shown and described.

2. In combination with a switch, the forward 100 end of which is pivoted to the rear portion of a movable frame 10, which is pivotally secured

on its forward end, and having upright flanges 24 connected with each other by the front and rear parts 15 and 17 of said frame passing underneath the track, the device whereby 5 the switch is thrown, and which device is attached to the car and capable of being brought in contact with either one of said flanges, whereby the frame, with the forward end of the switch, is moved to either side, all 10 as shown and described.

3. In a switch-movement, the combination, with the switch proper having its forward end pivotally connected to the rear end of a frame 10, the opposite and forward end of 15 which frame is also pivoted below the rail and adjacent to the switch, said frame hav-

ing vertical flanges 24 rising on each side of the switch and of those portions of the rail on which it rests, of stationary vertical flanges 14 outside of the movable flanges 24, whereby 20 these latter are protected from injuries, and also form with them a channel diverging toward the shifting device descending from the approaching car, insuring a gradual and proper contact necessary for throwing the 25 switch, all as shown and explained.

In testimony whereof I affix my signature in presence of two witnesses.

HENRY L. NODLER.

Witnesses:

N. ROCKHOLD,
CARL SPENGEL.
